Inventor

UNITED STATES PATENT OFFICE

THOMAS J. JOHNSON, OF FLINT, MICHIGAN

GAINING HEAD

Application filed September 6, 1928. Serial No. 304,309.

This invention relates to gaining heads, and it is an object of the invention to provide a gaining head which may be adjusted to increase or decrease either its width or its diameter so as to compensate for wear of the cutting tools carried by the head or to vary either the width or depth of the notches or grooves cut thereby.

It is a further object of the invention to provide a gaining head so constructed and arranged that the above-mentioned adjustments may be made without removing the head from the spindle on which it is mounted and without the use of shims or expansion collars.

Other and important objects of the invention will be apparent from a perusal of the following specification in connection with the accompanying drawing wherein is described and shown a preferred embodiment of my invention.

In the drawing:

Figure 1 is an end elevation, with parts broken away and in section, of my gaining head mounted on a spindle.

Figure 2 is a section on the line 2—2 of Figure 1.

Figure 3 is a view of the inner face of the male member of my gaining head.

Figure 4 is a view of the outer face of the female member of my gaining head.

Figure 5 is an elevation of an adjusting key adapted to be used in connection with my gaining head.

Figure 6 is an enlarged fragmentary section showing the details of the mounting of one of the edge cutting tools.

As shown in the drawing, the body of my gaining head is made of two parts, a male part 10 and a female part 11. The part 10 may be described as consisting of a circular member of suitable material, preferably forged steel, from which have been removed two diametrically opposite portions of substantially 90° ring sectoral shape, so as to leave two diametrically opposite outwardly projecting portions 12 of substantially the same shape as the removed portions, and which has formed on one side thereof and integral therewith a frusto-conical reinforcing

and strengthening portion 13 whose maximum diameter is somewhat greater than the inner diameter of the removed portions. Into the face of the member 10 opposite that on which the reinforcement 13 is formed there extends a circular recess 14 coaxial with the member and a circular counter-recess 15 whose diameter is equal to the inner diameter of the removed portions and which is coaxial with the recess 14.

The member 11 is similar to the member 10, as thus far described, and the same reference characters have been applied thereto.

From the bottom of the recess 14 and coaxial and integral with the member 10, there extends a cylindrical boss 16 through which and the member extends an axial bore 17. The end of the boss adjacent the bottom of the recess is slightly larger than the outer end thereof and is screw-threaded for a purpose 70 which will be apparent.

The reference character 18 indicates a circular disk of suitable material whose thickness is slightly less than the total depth of the recesses 14 in the members 10 and 11, and which is slightly smaller in diameter than the recesses 14. The disk 18 has therethrough an internally threaded axial bore 19 of substantially the same diameter as the outer end of the boss 16 and has formed on its 80 circumference gear teeth 20.

Extending through the member 11 and coaxial therewith is a bore 21 whose diameter is slightly larger than that of the outer end of the boss 16. Smaller bores 22, which are 85 located at such a distance from the center of the member 11 as to be externally tangent to a circle described about the axis of the member as a center and having a diameter substantially equal to that of the root circle 90 of the gear 18, also extend through the member 11.

On the outer faces of the outwardly projecting portions 12 of each of the members 10 and 11 there are provided two diametrically 95 opposite radial grooves 23 extending outwardly to the circumference thereof and on the opposite faces of the portions 12 and in registration with the grooves 23 two elongated recesses 24. In each of the grooves is 100

located a cutting tool or knife 25 which extends outwardly beyond the outer end thereof, and is provided on its opposite faces with a plurality of sharpened serrations inclined 5 in the direction of rotation of the head. The tools 25 are secured to the members 10 and 11 by bolts 26 extending through elongated slots 27 in the portions 12, and nuts 28 located in the recesses 24 and in screw-threaded 10 engagement with the bolts. The tools 25 obviously may be adjusted radially by loosening the nuts 28 and moving them inwardly or outwardly in the grooves 23.

A slot 29 which is inclined with respect to 15 the axis of the member, and also inclined in the direction of rotation of the head, extends into each of the portions 12 of the members 10 and 11 from the circumference thereof. As is clearly shown in the drawing, the direction 20 of inclination of the slots 29 in the members 10 and 11 with respect to the axes thereof is such that when the members are assembled, as hereinafter described, the slots in the member 10 are inclined oppositely to those 25 in the member 11 with respect to the axis of the head. Parallel with each of the slots 29 and outwardly thereof is a bore 30 which opens into the adjacent slot throughout the length thereof and is counter-bored at its 30 outer end. The outer end of the side of the slot 29, opposite that on which the bore 30 is located, opens into a recess 31 having a side wall inclined outwardly with respect to the side walls of the slot. In each of the slots 29 is located a cutting tool or knife 32 having a sharpened outer end. In each of the bores 30, and having its head located in the counter-bore at the outer end thereof, is a screw 33 on which is threaded a lifter 34 having a 35 portion projecting into the slot 29 and bearing against the rear end of the knife 32. In each of the recesses 31 and having one side parallel to and bearing against the adjacent side of the tool 32, and the opposite side 40 parallel to and bearing against the inclined wall of the recess 31 is a wedge 35 through which and threaded into the portion 12 extends a screw 36, having its head located in a counter-bore in the wedge, and which is 45 adapted to draw the wedge into the recess and thus hold the knife in position in the slot.

The tool 32, it is obvious, may be adjusted 50 in the slot 29 by unscrewing the screw 36 so as to loosen the wedge 35, and then moving the lifter 34 outwardly or inwardly by means of the screw 33 so as to move the tool outwardly or allow it to be moved inwardly, and then tightening the screw 36 so as to jam the 55 wedge against the side of the tool and the inclined side of the recess 31 in order to secure the tool in adjusted position.

The members 10, 11 and 18 are adapted to 60 be assembled, as shown in the drawing, with the boss 16 of the member 10 extending

through the bore 21 in the member 11, with the portions 12 of the members 10 and 11 in interfitting relation so as to form a substantially circular head, and with the member 18 positioned between the members 10 and 11 70 and located partially in each of the recesses 14 and in screw-threaded engagement with the boss 16.

When the parts of the gaining head are thus assembled, the head is adapted to be mounted on a conventional type of spindle, such as that indicated at 37, which has a reduced portion 38, and a collar 39 on the reduced portion, bearing at one end against the shoulder between the reduced and enlarged portions of the spindle. The gaining head is adapted to be mounted on the spindle 37 as shown in Figures 1 and 2, with the reduced end of the spindle extending through the bore 17 in the boss 16, and with the outer end of the collar 39 bearing against the outer face of the member 10, and is adapted to be secured thereon by a nut 40 screw-threaded on the outer end of the reduced portion of the spindle and bearing against the outer face of the member 11, through the intermediary of a collar 41 which surrounds the portion of the boss 16 which projects beyond the outer face of the member 11.

It will be noted that when the members 10, 11 and 18 are assembled as shown in the drawing and hereinbefore described, teeth of the gear 18 extend into the inner ends of the bores 22. As shown in Figures 2 and 5, there is provided a key 42 having formed on one end thereof a handle 43, and on the opposite end thereof, which is adapted to enter one of the bores 22, gear teeth 44 adapted to mesh with the teeth 20 on the gear 18.

It will now be obvious that to adjust my gaining head so as to increase or decrease its width, it is only necessary to loosen the nut 40, insert the toothed end of the key 42 in one of the bores 22 so that the teeth thereon mesh with teeth on the gear 18, turn the key by means of the handle 43 so as to cause rotation of the gear 18 and cause it to move outwardly or inwardly on the boss 16, and thus farther separate the members 10 and 11 110 axially or allow them to be moved closer together axially when the nut 40 is subsequently tightened. It will be obvious that when the members 10 and 11 are farther separated axially the width of the slot cut by the head 115 will be increased, and when they are moved closer together axially the width of the slot cut by the head will be decreased.

Though I have shown and described a preferred embodiment of my invention, it is 120 to be understood that this has been done merely by way of example and not with the intention of limiting my invention thereto, and that the scope of my invention is limited only 125 by the appended claim.

I claim:

In a device of the class described, a body portion including two parts each of which includes a substantially circular central portion, diametrically opposite projections extending outwardly from each of the central portions and adapted to interfit with the projections on the other central portion to form a substantially circular head, axial recesses 5 formed in the juxtaposed faces of the two central portions, a boss extending axially from one of said central portions and into an axial bore in the other of said central portions, an adjusting member located in said 10 recesses and in screw-threaded engagement with said boss, gear teeth on the periphery of said adjusting member, and a bore through one of said central portions through which a key having gear teeth thereon is adapted to 15 be inserted to engage the teeth thereof with the teeth on the adjusting member to adjust the two parts of the body portion axially. 20

In testimony whereof I affix my signature.
